CLOCK RADIO

Ken Kawamura, Katano, and Takao Okada and Hironosuke Koda, Kyoto, Japan, assignors to Matsushita Electric Industrial Co., Ltd., Osaka, Japan

Filed Apr. 20, 1973, Ser. No. 353,172

Claims priority, application Japan Oct. 20, 1972

Term of patent 14 years

Int. Cl. D14—03
U.S. Cl. D56—4 B

FIG. 1

FIG. 2

FIG. 1 is a right side, top and front perspective view of a clock radio, showing our new design; and

FIG. 2 is a left side, top and rear perspective view.

Portions of the figures are shaded to indicate contrast in appearance, and portions are diagonally lined to indicate transparency.

We claim:

The ornamental design for a clock radio, as shown and described.
